(57) **CLAIM**

The ornamental design for a decorative tire, as shown and described.

DESCRIPTION

FIG. 1 is a front elevational view of a decorative tire of the present invention;

FIG. 2 is a front elevational view of a second embodiment of the tire shown in FIG. 1; and,

FIG. 3 is a front elevational view of a third embodiment of the tire shown in FIG. 1.

The broken line showing of a tire in FIGS. 1-3 is for illustrative purposes only and forms no part of the claimed design.

The rear and side elevational views, and the top and bottom plan views, are plain and unornamental and not part of the claimed design.
